(57) **CLAIM**

The ornamental design for shoe, as shown and described.

DESCRIPTION

FIG. 1 is a top perspective view of a shoe, showing our new design;
FIG. 2 is a top view of the shoe shown in FIG. 1;

FIG. 3 is a bottom view of the shoe shown in FIG. 1;

FIG. 4 is an inner side view of the shoe shown in FIG. 1;

FIG. 5 is an outer side view of the shoe shown in FIG. 1;

FIG. 6 is a front view of the shoe shown in FIG. 1; and,

FIG. 7 is a rear view of the shoe shown in FIG. 1.

In the drawings, the broken lines in FIGS. 2-7 depict portions of the design that form no part of the claim.
